(57) **CLAIM**

The ornamental design for an instrument panel for an automobile, as shown and described.

DESCRIPTION

FIG. 1 is a perspective view of an instrument panel for an automobile showing our new design;

FIG. 2 is a top view thereof;

FIG. 3 is a bottom view thereof;

FIG. 4 is a front view thereof;

FIG. 5 is a left side view thereof; and,

FIG. 6 is a right side view thereof.

The claimed design is indicated by the relatively dark portions in FIGS. 1-6, while the relatively light portion in FIG. 3 is environmental and forms no part of the claimed design.
